(57) **CLAIM**

The ornamental design for a firefly lamp, as shown and described.

DESCRIPTION

FIG. 1 is a front, top perspective view of a firefly lamp, showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3;

FIG. 12 is an enlarged view of detail 12 in FIG. 7;

FIG. 13 is a front, top perspective view of a firefly lamp in a second configuration of use; and,

FIG. 14 is an enlarged view of detail 14 in FIG. 13.

The dashed broken lines in the figures illustrate portions of the firefly lamp that form no part of the claimed design.

The dash-dot-dash broken lines are for notating enlarged views and form no part of the claimed design.
